UNITED STATES PATENT OFFICE.

JOHN B. PUTROW, OF WESTBOROUGH, ASSIGNOR TO W. B. JOHNS, OF ANTIGO, WISCONSIN.

SHINGLE-SAWING MACHINE.

SPECIFICATION forming part of Letters Patent No. 423,953, dated March 25, 1890.

Application filed September 20, 1887. Renewed January 4, 1890. Serial No. 335,923. (No model.)

To all whom it may concern:

Be it known that I, JOHN B. PUTROW, a citizen of the United States, residing at Westborough, in the county of Taylor and State 5 of Wisconsin, have invented a new and useful Improvement in Shingle-Sawing Machines, of which the following is a specification.

My invention relates to an improvement in shingle-sawing machines; and it consists in 10 the construction and arrangement of the parts thereof, which will be more fully hereinafter described, and particularly pointed out in the claims.

In the accompanying drawings, wherein 15 like letters and figures of reference indicate similar parts in the several views, Figure 1 is a perspective view of my improved form of machine. Fig. 2 is a side elevation. Fig. 3 is a rear elevation. Fig. 4 is a top plan view. Fig. 5 is a longitudinal vertical section on the line $x-x$ of Fig. 4. Fig. 6 is a transverse vertical section on the line $y-y$ of Fig. 5, looking in the direction of the arrow. Fig. 7 is a horizontal sectional view on the line $z-z$ of Fig. 3. Fig. 8 is a detail perspective view of the 20 saw-arbor and various connections. Fig. 9 is a vertical sectional view on the line $w-w$ of Fig. 2. Figs. 10, 11, 12, and 13 are detail views of portions of the construction.

30 A A indicate the base-strips, which are formed with grooves or channels $a-a$, in which the flanges $b-b$ on the lower portions of the sides B B of the main supporting-frame have movement. The base-strips are united by cross-strips A' A' and the sides B B by front upper and lower cross-beams B' B' and rear upper and lower cross-beams B³ B⁴.

In suitable journal-boxes c c, secured on the top portions of the base-strips A A, a transverse shaft S is mounted, on which cog-wheels s s are keyed and engage with rack-surfaces b' b', formed with the upper edge of the lower longitudinal beams B⁵ of the sides B. On one end of the said shaft S, on the outside of one 45 of the boxes c, a pinion s' is mounted, which is adapted to be engaged by one end of a double pawl s², pivotally connected to the side of a hand-lever s³, which is mounted on a shaft S inside and adjacent to the wheel 50 or pinion s'. Upon the outer side of the base-strip A, in engaging proximity to the

pinion s', a locking-pawl s⁴ is mounted, which is adapted to lock the said pinion s' against movement. By means of this construction the whole frame, comprising the sides B B and their connecting cross-beams, can be moved to the rear or front, and the belt operating the machine thereby tightened or loosened, as may be desired, and if the belt should break and be shortened by splicing 60 the machine can be readily accommodated to the decrease in the length of the belt without necessitating the substitution of a new belt.

The rear cross-beams B³ and B⁴, uniting the side frames B B, are adapted to support the 65 saw-arbor and its adjustable boxes. The lower beam B⁴ is constructed with a central cup or socket B⁶ and the upper beam B³ with two inwardly-projecting angle-lugs b² b².

The saw-arbor frame C is constructed, es- 70 sentially, in the form shown, having the lower enlargement c' formed with a diamond-shaped socket c², adapted to receive a sectional adjustable diamond-shaped box c³, which surrounds the lower end of a vertically-mounted 75 shaft S', and held in adjustment therewith by four set-screws s⁵ s⁵, passing through the lower enlargement c' of the frame C, each one of said set-screws engaging with the plain faces of the said sectional box c³. The lower portion of the frame C is extended to give un- 80 impeded play to the single lower flange C² of the belt-pulley C', which is mounted on the shaft S'. The upper end of the frame C is formed with an integral half-box c⁴, which 85 rests in and is adjustably held between the angle-lugs b² of the upper beam B³ by set-screws s⁶, arranged on each side thereof. The upper end of the shaft S' is formed with an integral saw-disk S², to which the circular 90 saw S³ is secured in a horizontal position by machine-screws.

The lower enlargement c' of the frame C is mounted and held in the socket B⁶ of the beam B⁴ by two set-screws s⁷, having set-collars s⁸. Through the medium of these latter screws the frame C, and consequently the saw S³, can be adjusted slightly when for any desirable purpose it becomes necessary. When the shaft S' and frame C have thus 100 been mounted, a half-box c⁵ is screwed to the half-box c⁴ in the upper part of the frame C,

and the said parts secured in operative position.

On the top portion of the side frames B B hollow side saw-guards D D' are mounted, which slightly widen or diverge from the front toward the rear of the machine. The saw has freedom of play within these guards, and injury to the operators is thereby prevented. The guard D' is constructed wider than the guard D and forms a sawdust-spout. The edge of the guard D' is open and provided with a hinged arm D², which closes over the said opening. The said arm is hinged at the point d in the forward part of the machine and adapted to be retained in a permanent closed position by a screw s⁸, passing through extensions d', formed with the rear of said arm, and into the guard D'. Said arm D² enables access to be readily had to the interior of the guard D', acting as a dust-spout, and enables the same to be readily cleared or relieved from any choking or packing that may occur. Hinged to the rear of the guards D and D' is a rear guard D³, which fits over the rear of the saw and is adapted to be raised therefrom when desired. Integrally formed with one side of the rear guard D³, adjacent to the guard D', is an extended spout D⁴, which registers with the opening in the guard D' when lowered, and when raised through its hinged connection, as shown, the sawdust which may clog in the spouts can be readily removed.

On the inner top portion of the guards D and D' the carriage-guideways E are bolted, and consist of angle-irons having outer grooved faces. The carriage F consists of a rectangularly-shaped open frame having slots f formed in the outer ends of the transverse bars F' thereof, and adjacent to said slots f the longitudinal end connecting-bars F² are integrally formed with the said transverse bars F' and carry rollers f' on their inner faces, which engage with the lower portion of the recesses of the angle-irons or guideways E. Over the top inner edges of the bars F² smaller frictional rollers f² are mounted in angle-irons f³, fitted over the top and outer faces of the bars F², and resting in recesses formed therein. The lower inner portions of the transverse bars F' are formed with flanges 1 1, which are engaged by grooved extensions 2 2, integrally formed with the adjustable dogs F³, mounted parallel with the end bars F², but adjustable in a plane parallel with the transverse bars F'. Running parallel with the end bars F² and adjacent thereto, and having bearing in the transverse bars F', are two small rock-shafts 3 3, having upward projections 4 4 near each end thereof, which are in pivotal connection with link-rods or pitmen 5 5, said rods or pitmen 5 being secured at their opposite ends in slots formed in the dogs F³. The outer ends of the rock-shafts 3 are provided with handles 6 and 7. The outer end of the one rock-shaft 3 is formed with a loop 8 in its end, in which one

end of the vertical portion 9 of the handle 7 is secured. Over the end of this rock-shaft a bracket 10, having a top angular projection 11, is mounted, the end of the said shaft passing through an elongated slot 12, formed in said bracket, and allowing a vertical movement thereof. The vertical portion 9 of the handle 7 is encircled by a coiled spring 13, which bears against the loop 8 at its lower end and the angular projection 11 of the bracket 10 at its upper end. The lower end of the said bracket 10 is provided with a stud or pin 14, (see Fig. 10,) projecting from the inner face thereof, adapted to engage with slots 16, cut in the lower edges of the transverse bar F', adjacent thereto, and pivotally secured in connection with the under side of the handle 7 is a lever 15, having a bifurcated or forked end 17, which encircles the handle 7 and bears on the top portion of the extension 11 of the bracket 10, and is adapted to force the said bracket downward to disengage the pin 14 from the slots 16 in adjusting the dog in connection with the rock-shaft with which the mechanism just described is connected. The bracket 10 is also capable of a swinging movement through its slotted connection with the end of the rock-shaft, and the stud or pin 14 thus caused to engage with the slots 16 at some distance away from the line of position of the rock-shaft in tightening the adjustment of the dog F³ in connection therewith.

Secured to the rear transverse bar of the carriage are two bracket journal-boxes 18, in which is journaled a shaft 19, having angular end projections 20. The one angular end projection 20 is formed with an operating-handle 21, and to each of said projections links 22 are secured. The other ends of said links are connected to a transversely-arranged frame F⁴, having grooves formed in its extending ends, which rest upon the rock-shafts 3 and have longitudinal movement thereon. The central portion 23 of this frame F⁴ slightly depends and has a slot 24 cut therethrough, in which a wooden strip 25 is driven, projecting below the lower edge, and thereby prevents the saw from striking the metal of the said frame. This frame is adapted to aid in the feed and retention of the block from which the shingles are formed. The dogs F³ are also provided with slots 27, in which pieces of wood are driven for a similar purpose as in the frame F⁴. The front transverse bar has saw-guards 26 mounted in connection therewith, which are curved and have inner slotted ends, in which strips of wood are also mounted for a purpose similar to those mounted in the dogs F³ and frame F⁴.

On the forward portion of the machine, in cross-beams B' and B², a tilting table G and its connections are mounted. This device consists, essentially, of the tilting table G, constructed with two longitudinal grooved arms g g, longitudinally adjustable on the plate g', which connects the two arms. An upright

G' is provided, which is constructed hollow and supported by the bars B' B². The upper portion of the upright G' is constructed cylindrical and passes through a square opening b⁴ in the upper cross-beam B', having lugs b⁵ on its transverse sides. A sectional boxing 28 28, having grooves 29 in each of its parts, is fitted in the opening b⁴ and around the upper cylindrical portion of the upright G', being adjustable in and held in a fixed position in said opening by set screws s⁹, passing through lugs b⁵, integrally formed with the top portion of the beam B'. The lower portion of the upright G' is constructed of a nearly-rectangular configuration, the extreme lower end being formed with projecting open ends 31, in which a lever G² is fulcrumed. The one end of the lever G² is pivotally secured in the hollow lower beam B² by a screw s¹⁰, passing through said beam and the end of the lever. The opposite end of the said lever G² is connected to the lower end of a lifting rod or bar G³, which passes up vertically through both beams B' and B², and is secured at its upper end to the crank 32 of an operating hand-lever 33, having a spring-actuated stop-arm 34 pivotally secured in connection therewith. The hand-lever 33 has a slot 35 therein, through which a flat arm 36 passes, which has a notch or notches 37 formed therein. This arm 36 is mounted in projections 38 and 39, secured to the top portion of one of the sides B. The projection 38 is stationarily mounted and the projection 39 pivotally mounted, so as to have a yielding movement. The one end of the arm 36 is pivoted in the projection 39, and the opposite screw-threaded portion 40 passes through and has movement in an opening in the projection 38. An ordinary nut 41 is placed on the screw-threaded portion 40 of the arm 36 on one side of the projection 38, and a clamping or winged nut 42 is placed thereon on the opposite side of the projection 38. By this construction the tilting table can be raised or lowered in a vertical plane, the extent of adjustment being regulable by the adjustable arm 36 in connection with the hand-lever 33.

The top portion of the standard or upright G' has a yoke G⁴ secured thereto by means of a screw s¹², said yoke G⁴ having right-angular lugs 43, in and between which a smaller yoke G⁵ is adjustably held by set-screws s¹³, passing through the lugs 43 and engaging with a cylindrical portion g⁵ of the yoke G⁵. The upper portion of the yoke G⁵ is formed with angular upwardly-projecting lugs 44, in and between which a slightly-enlarged depending portion of the plate g' is pivoted. The yoke G⁵ is also formed with an integral projection g⁶, having an aperture in its outer end, through which a screw s¹⁴, depending from the one outer end of the plate g', passes, having a nut 45 in engagement therewith on each side of the end of the extension g⁶. By means of this extension the tilting table is steadied in its movement. To the lower central portion

of the cylindrical portion g⁵ of the smaller yoke G⁵ the upper end of a rod 46 is secured, which has a collar 47 mounted on the lower portion thereof, against which a coiled spring 48, encircling said rod, rests. The lower end of said spring rests normally on the top portion of a block 49, carrying a friction-roller 50 in its lower end. The rod 46 passes into an aperture formed in the top portion of the block 49, and the roller 50 in the lower end of said block plays transversely in a groove 51, formed in the top surface of a tilting block 52, pivotally mounted in the lower portion of the upright or standard G'; and having the end of a draw-rod 53 connected to its lower portion, the opposite end of said draw-rod 53 being secured to one end of a connecting-link 54, which projects through the lower cross-bar B³ and is secured at its opposite end to the lower portion of a vertical rod 55, which is stepped in lug 56 on the said beam and projects upward and passes through a lug 57, formed with the upper portion of the side frame B. A handle 58 is secured to the upper part of this rod 55 adjacent and conveniently situated to the operator, and by which the table G may be tilted to give the proper angle of cut. The block 49 is limited in its movement toward either side of the upright G' by set-screws s¹⁵, passing through the said upright and extending into the hollow portion thereof, and adjustable from the outside, and held in adjustment by the set-nuts s¹⁶. In addition to the tilting mechanism just described, the upright entire may be fixedly adjusted toward either side of the machine by moving the sectional boxes mounted in the opening in the top cross-beam B'. 105

H and H' represent saw-adjusting devices, which are secured to the flanges formed with the inner top portions of the side frames B B'. The adjusting device H' consists of a casting 58', having an opening 59 therein, in which a box 60 is mounted, which has a feather 61 engaging with a groove 62 in one side of the opening 59. The box 60 is open at the top and closed at the bottom thereof, with an aperture in the said bottom, through which an adjusting-screw s¹⁷ passes, and into the lower portion 63 of an angular arm 63', fitted in said box, the upper angularly-projecting portion 64 of which has an aperture formed in its outer end, through which a billet 65 of wood is driven, so that it will slightly depend from the lower surface thereof. The said casting 58' is also provided with a projection 66, through which a set-screw 67 passes from the under side, and is formed with a hollow end, in which a small billet of wood 68 is driven, and is mounted in alignment with the wooden depending billet 65. 115

The device H consists, essentially, of a casting 66', which is longitudinally adjustable in connection with the side frame B, to which it is attached, and is provided with an elongated arm 70, having a depending slotted projection 71 at one end and a hollow apertured slightly-

depending projection 72 at the opposite end. A lever 73 is fulcrumed in the projection 72, and the end 75 thereof adjacent to its fulcrumed point is slightly reduced and rounded, 5 and is adapted to engage with a slot 75 in the edge of a vertically-sliding block 74, moving in the aperture formed in the end of the projection 72. The top of the block 74 is formed with a flanged projection 75', adapted to form 10 an extended surface at this point. The opposite end of the lever 73 passes through the slot in the projection 71 and is formed with a handle 76 for operating the same, an adjusting-screw s^{19} passing up through the bottom 15 of the projection 71 and adapted to limit the movement of the lever 73. The object of this device is to temporarily raise the saw by means of the top extended surface of the vertically-sliding block 74 engaging with the under side of said saw, and which is raised and 20 lowered by the lever 73.

Back of the elongated extension, as just described, two ears or lugs 77, 77 are integrally formed with the casting, in which a lever 78 25 is fulcrumed. The rear end of the lever 78 is adjustable by means of a screw s^{20} , passing through a slot 79, formed in a lug 80, formed with the casting 66', and into the handle of the lever 78. The rear portion of the said 30 lever is curved upwardly, with an aperture, through which a small wooden billet 81 is driven, depending from the lower side of the lever. Below the position of the lever and integrally formed with the lower end of the 35 casting is a projection 82, which has an aperture therein, through which an adjusting-screw 83, having a hollow end, passes from the under side of the said projection, the said hollow portion of the screw 83 having a wooden, 40 billet 84 driven therein, which projects upwardly in alignment with the wooden billet 81. This device has the same function in relation to the saw as the similar constructions of the device H. On the elongated arm 70 45 three frictional rollers 85 are mounted in horizontal alignment and are adapted to aid in the easy movement of the wooden block passing thereover and against the same.

On the rear portion of each of the guards 50 D and D' a spring-buffer is mounted, and consists, essentially, of an apertured block 86, having a short rod 87, encircled by a coiled spring 88, mounted therein, the said rods 87 having enlarged heads 89, against which the 55 carriage is adapted to strike in its rearward movement and be thereby cushioned.

The entire machine is readily adjustable, is complete in mechanism for operating upon a shingle in any desired and well-known manner, is convenient and accessible, and, combining the various mechanisms as it does, is comparatively inexpensive in its manufacture.

Having thus described my invention, I 65 claim—

1. The combination of the base-strips A, having the grooves or channels a , the side

frames B, having the flanges b and the rack-surfaces b' , the saw, its shaft and belt-pulley supported by said frames b , the shaft S, the cog-wheels s , the pinion s' , and the hand-lever s^3 , substantially as described.

2. The combination of the side frames B, the upper cross-beam B^3 , formed with inwardly-extending lugs b^2 , having set-screws mounted 75 therein, the lower cross-beam B^4 , having the rectangular socket B^6 , the frame C, the rectangular saw-arbor bearing at the lower end of said frame fitted in said socket, the half-bearing c^4 at the upper end of the frame, the cap c^5 , the vertical saw-arbor mounted in the rectangular bearing and between the cap c^6 and half-bearing c^4 , and the set-screws bearing on the upper and lower ends of the frame to adjust the same, as set forth. 85

3. In combination with the side frames B, the hollow guards D and D', one of which forms a sawdust-spout, the horizontally-movable hinged arm D^2 , and the rear hinged guard D^3 , having the extended spout D^4 formed 90 therewith, substantially as described.

4. The combination, with the side frames B, having the guards D and D' secured to the upper portion thereof, and rotatable saw, of the guideways or tracks E, the carriage F, and the 95 spring-buffers mounted on the rear portion of the guards D and D', substantially as described.

5. The combination, with the upper longitudinal and parallel guideways or tracks E, 100 having the outer horizontal grooved faces, of the carriage F, having the transverse bars F', formed with vertical slot f on their under side to receive the tracks E, and horizontal bars F², connecting the ends of bars F' and located 105 adjacent to the grooved faces of the tracks, and having vertical and horizontal friction-rollers f' , f^2 to bear against corresponding faces in the grooved sides of the guideways E, as described and shown, substantially as 110 described.

6. The combination of the bars F', the forward one of which is provided with slots 116 in its lower edge, one of the rock-shafts 3 and its dog F³, the handle 7, the bracket 10, provided with a slot, through which the end of the rock-shaft passes, and having a projection 12, the spring 13, the stud or pin 14, and the lever 15, substantially as described. 115

7. The combination, with the bars F', the forward one of which is provided with slots in its under edge, and the slotted bracket 10, having a projection to engage said slots, of the dogs F³ in movable connection with said bars, provided with slots, through which a shingle 125 or strip of wood is inserted, the rock-shafts 3, connected to said dogs, one of said shafts extending through said slotted bracket, the handle 6 in connection with one rock-shaft, and the handle 7 in connection with the other, 130 substantially as described.

8. The combination, with the rear bar F' of the carriage F and the rock-shafts 3, of the bracket-boxes 18, the rock-shaft 19, having

projections 20, one of which is formed into a handle 21, the links 22, and the transversely-arranged frame F⁴, having grooves in its extended ends adapted to engage with and slide 5 on the rock-shafts 3, substantially as described.

9. The combination, with the guide-rails of the frame, of the carriage F, provided with bars F', movable on said rails, the dogs F³, 10 movable transversely of the frame, transversely-mounted frame F⁴, movable longitudinally thereof, and handles and connections for moving said dogs and frame, the said dogs, their handles, and frame F⁴ being located 15 within the limit of the rails and bars F', substantially as specified.

10. The combination, with the guide-rails of the frame, of the carriage F, provided with bars F', movable on said rails, the vertically-slotted dogs F³, movable transversely of the frame F⁴, vertically slotted and mounted longitudinally thereof, handles and connections for moving said dogs and frame F⁴, and strips 20 of wood in the slots of the dogs and frame F⁴, 25 the said dogs and frame F⁴ and their handles and connections being located within the limit of the rails and bars F', substantially as specified.

11. The combination, with the cross-beams, 30 of the hollow upright G', seated in said beams, as described, and having a vertical transverse and oscillating adjustment therein, and a tilting table G, mounted on the upper end of the upright, substantially as described.

12. The combination, with the cross-beams B', having the central square opening b⁴ and lugs b⁵ on each side of said opening, having adjusting set-screws s⁹ therein, and the beam B², 35 constructed hollow, as set forth, of the upright G', constructed cylindrical at its upper portion and substantially rectangular at its lower portion and hollow throughout its length, the grooved boxes 28, the yoke G⁴, and the tilting table G, substantially as described.

13. In combination with the upper part of the upright G' of the yoke G⁴, the yoke G⁵, having the extension g⁶, the table G, constructed as set forth, mounted in connection 45 with the yoke G⁵, the rod 46, having a collar 50 47 and coiled spring 48, the block 49, carrying a frictional roller 50 in its lower end, the tilting table 52, the draw-rod 53, the connecting-link 54, the vertical rod 55, having an operating-handle 58, and the set-screws s¹⁵, substantially as described.

14. The combination, with beams B' and B², of the upright G', having the lower projecting ends 31, the lever G², the lifting-rod G³, the slotted hand-lever 33, having a crank 55 32 and a spring-actuated stop-arm 34, the adjustable arm 36, having a notch or notches 37 therein, the stationary projection 38, and the projection 39, movably mounted, as set forth, substantially as described.

15. The herein-described tilting table, comprising the centrally-pivoted transverse plate

g' and the longitudinally-adjustable arms g g, mounted on the ends of said plate g', as set forth.

16. The combination, with one of the side frames B, of the saw guiding and holding device H', consisting, essentially, of the casting 58, having an opening 59, provided with a groove 62, the vertically-adjustable box 60, having a feather 61, the angular arm 63', 75 carrying a depending billet 65 in its angularly-projecting portion 64, the projection 66, the hollow-ended set-screw 67, carrying a billet 68, and the adjusting-screw s¹⁷, substantially as described. 80

17. The combination, with one of the side frames B, of the casting 66', having the elongated arm 70, provided with a depending slotted projection 71 at its one end and a slightly-depending hollow projection 72 at its opposite end, a lever 73, fulcrumed in the projection 72 and passing through the slot in the projection 71 and having its forward end reduced and rounded, and the vertically-sliding block 74, having a recess 75, with which the 90 reduced end of the lever 73 engages, and an upper flanged extended surface adapted to bear against the under side of the saw, substantially as described.

18. The combination, with one of the side frames B, of the casting 66', adjustably mounted in connection therewith, having lugs 77 and 80 integrally formed therewith, the lever 78, provided with an upwardly-curved apertured end and fulcrumed in the 100 lugs 77, and adjustably secured to the lug 80 by a set-screw s²⁰, passing through a slot in said latter lug and into the lever, the depending wooden billet 81, carried in the aperture in the end of the lever 78, the projection 82, 105 the adjusting-screw 83, and the wooden billet 84, substantially as described.

19. The combination, with the frame having the side rails, saw-arbor, and saw, of the casting 66', provided with upper and lower projections carrying billets, frictional rollers 85, mounted on said casting, and a carriage movable upon said rails, substantially as specified. 110

20. The combination, with the guards D and D', of the apertured block 86, mounted in the rear portion thereof, short rods 87, having enlarged heads 89, mounted in said blocks, the coiled springs 88, surrounding said rods 87, and the saw and carriage, substantially as 120 described.

21. In combination with the stationary strips A of the base-frame, the side frames B, carrying the entire operating mechanism of the shingle-sawing machine, including the 125 saw, its arbor, and belt-pulley, the said frames B being movable in grooves or ways of the frame A, and mechanism, substantially as described, to actuate the frames B, as set forth. 130

22. In combination with the hollow guards D D', provided on the side frames of the

- shingle-sawing machine, one side of guard D' being open, the horizontally-movable hinged arm D², for closing the open side of said guard, as set forth. 35
- 5 23. In combination with the side frames B, having the guideways or tracks E, the carriage F, running in the guideways or tracks, and the elastic buffers mounted at one end of the tracks to receive the impact of the carriage, as set forth. 10
- 15 24. In combination with the movable saw-carriage, the movable dogs located within the carriage-frame and movable transversely, handles and their connections for moving said dogs, a longitudinally-movable frame F⁴, located between the dogs, and connections for moving said frame, said frame-handles and connections being located within the dimensions of the supporting frame, substantially 20 as described. 25
- 25 25. The combination, with the frame, of the longitudinally-movable carriage mounted thereon, the frame F⁴, supported by said carriage and arranged transversely to the same, and the lever fulcrumed on the carriage and connected to the frame D⁴ to move the same longitudinally independent of the carriage, as set forth. 30
- 30 26. The combination of the standard, the yoke G⁵, pivoted to the upper end of the same and having a lateral extension g⁶, the table pivoted to the said yoke, and the set-screw inserted vertically through the table and en-
- gaging the end of the said extension g⁶, as set forth. 35
27. The combination, with the upper and lower end bars B' B² of the frame, of the vertical hollow standard G', seated in both bars, a tilting table G, mounted upon the same, and adjusting appliances, substantially such as 40 parts 46 49 52 53 G², and operating-connections located in and adjacent to said standard to elevate, tilt, and transversely move the table, substantially as specified. 45
28. In combination with the hollow upright G', the table G at the top of the upright, the tilting devices for the table located within the upright, the adjustable means for the tilting devices, and the elevating mechanism for the upright G', as set forth. 50
29.
